UNITED STATES PATENT OFFICE

104,526

DESIGN FOR AN ANTENNA COUPLER HOUSING

Leon S. Brach, East Orange, N. J.

Application December 17, 1936, Serial No. 66,596

Term of patent 7 years

To all whom it may concern:

Be it known that I, Leon S. Brach, a citizen of the United States, residing at East Orange, in the county of Essex, State of New Jersey, have invented a new, original, and ornamental Design for an Antenna Coupler Housing, of which the following is a specification, reference being had to the accompanying drawing, forming a part thereof.

Figure 1 is a top plan view of the device.

Figure 2 is a side elevation of the device.

Figure 3 is an end elevation of the device.

Figure 4 is a view of the device looking from the bottom toward the top.

I claim:

The ornamental design for an antenna coupler housing as shown.

LEON S. BRACH.
